UNITED STATES PATENT OFFICE.

CLIFFORD H. PEEK, OF EAST AURORA, NEW YORK.

AMUSEMENT DEVICE.

1,094,011.

Specification of Letters Patent. Patented Apr. 21, 1914.

Application filed February 26, 1913. Serial No. 750,785.

To all whom it may concern:

Be it known that I, CLIFFORD H. PEEK, a citizen of the United States, residing at East Aurora, in the county of Erie and State of New York, have invented a new and useful Improvement in Amusement Devices, of which the following is a specification.

This invention relates to amusement or educational devices and comprises a plurality of strips of paper or other flexible material which are adapted to be interwoven to form designs.

The object of the invention is to produce a simple and inexpensive amusement device of this kind, by means of which a large variety of designs can be produced and which offers interesting and instructive entertainment.

In the accompanying drawings, Figures 1 and 2 represent two sheets of flexible material which are slotted to form the strips which are required for the amusement device embodying the invention. Fig. 3 shows the two sheets in position for weaving. Figs. 4 and 5 show the sheets during successive steps in the weaving operation. Fig. 6 shows the sheets interwoven to form a design. Fig. 7 shows the reverse side of the two interwoven sheets shown in Fig. 6. Fig. 8 shows a design made by two larger sheets.

Like reference characters refer to like parts in the several figures.

A A' represent two elements or sheets of paper or other flexible material which are preferably of contrasting color or appearance. Each of these elements or sheets consists of a plurality of strips which are arranged in two groups, the strips of each group being parallel to each other and extending at an angle to the strips of the other group. Each of the strips of one group is connected at one end to one edge of the sheet or element and the strips of the other group are connected to an adjacent edge of the sheet or element. The free end of each of the strips of one group may be connected respectively to the free end of a corresponding strip of the other group, so that the two groups of connected strips form a plurality of substantially L-shaped strips, each of which is connected at its opposite ends to two adjacent sides of the element.

In the preferred construction of the device shown in the drawings, the strips are

formed integrally with the sheets. Each sheet is provided with a plurality of parallel angular or L-shaped slits, the two parts of which extend parallel to two adjacent sides of the sheet and which divide the inner portion of the sheet into a plurality of angular or L-shaped strips of equal widths. The opposite ends of these strips are joined by marginal or border portions *a* of the sheet at two sides thereof, and the sheet is preferably provided with marginal or border portions *a'* at the remaining sides thereof, substantially similar in dimensions to the marginal portions *a*. The angular strips decrease in size from one corner of the sheet to the diagonally opposite corner. Six of these strips are shown in the drawings, which are marked 1, 2, 3, 4, 5 and 6, respectively. 7 represents a projection which enters the recess or cut-out portion of the last strip. The sheets may be of any desired size and may be provided with any number of strips. The strips of the two sheets may be interwoven in various different ways to form different desired designs or patterns. For example, the strips can be interwoven in the following manner for forming the design shown in Fig. 6. For sake of brevity the sheet which is shown with the diagonal shade lines will be hereinafter designated as green and the other sheet as white:—The strips of each sheet are all passed through the outer or longest slit in the other sheet, so that the strips of one sheet will cover the strips of the other sheet, the white strips being shown underneath the green ones in the case illustrated. Strip 1 of the white sheet is then pulled out from underneath the green strip 2 and placed over green strips 2 and 3, see Fig. 4, under green strip 4, and over green strips 5 and 6. The corner of the white strip 1 is then placed under the projection 7 of the green sheet. When this is completed, the two sheets will appear as shown in Fig. 4. The strip 2 of the white sheet is then withdrawn from underneath the strip 1 of the green sheet, Fig. 5, and passed over strip 1 of the green sheet, under green strip 2, over green strips 3, 4 and 5 and its point is placed under the point of strip 6 of the green sheet. The sheets then appear as shown in Fig. 5. This operation is continued, one white strip at a time being withdrawn and interwoven with the green strips until the design shown in Fig. 110

6 is completed. Any other method for interweaving the strips may be employed.

A large number of different designs can be produced by interweaving the strips differently, and different effects can be produced by making the same design in different colors. For each design, a corresponding design in which the colors are interchanged is produced on the reverse side of 10 the two sheets. For example, the design shown in Fig. 7 is the one that will be formed on the reverse side of the two sheets shown in Fig. 6.

Fig. 8 illustrates another design which 15 can be produced by means of larger sheets, or sheets having a larger number of strips.

The sheets after having been interwoven can be again separated and can be used repeatedly.

20 While the angular strips are preferably formed by cutting angular slits in the sheets and are, therefore, integral parts of the sheets, it will be evident that sheets of a similar nature and adapted to be interwoven in a similar manner could be formed by securing together at their ends separate angular strips.

I claim as my invention:

1. An amusement device consisting of two 30 elements of flexible material, each comprising a plurality of parallel angular strips, the ends of which are connected at two adjacent sides of the element and the strips of one element being adapted to be inter-

woven with the strips of the other element 35 to form a design, substantially as set forth.

2. An amusement device consisting of two sheets of flexible material, each sheet comprising a plurality of right angular strips arranged parallel to each other and having their ends joined at two sides of the sheet, said strips of the two sheets being adapted to be interwoven to form a design, substantially as set forth.

3. An amusement device consisting of two 45 quadrilateral sheets of flexible material, each sheet having its inner portion divided into a plurality of parallel strips, said sheets having a border adjacent to their outer edge, and said strips being joined to two 50 adjacent sides of the border, substantially as set forth.

4. An amusement device consisting of two elements of flexible material, each element comprising a plurality of strips which are 55 connected at one end and which project from two adjacent sides of the element, the strips which are secured to one side of the element being parallel to each other and extending at an angle to the strips secured to the other side of the element, substantially as set forth.

Witness my hand, this 15th day of February, 1913.

CLIFFORD H. PEEK.
